TOP BURNER ASSEMBLY

John T. Marvin, Fairview Village, and Birchard
L. Matthews, Lakewood, Ohio

Application December 24, 1934, Serial No. 758,992

3 Claims. (Cl. 158—99)

This invention relates to a unitary burner assembly. As designed, the structure consists of a cluster of several burners, a gas cock, and a lighter therefor, all of which are joined together rigidly as a unit, whereby a minimum of labor and expense may be necessary for their manufacture, installation and maintenance.

It is an object of this invention to provide a plurality of burners, all rigidly joined together, and removable as a unit from an installation.

A further object is to provide, with such an assembly, a lighter, rigidly mounted therewith, and selectively removable therefrom, for igniting any of the burners.

15 A further object is to provide an assembly of four rigidly connected burners, a valve means for operating them, and rigidly mounted together with them.

20 A further object is to provide an assembly of this kind wherein a front manifold is eliminated.

25 A further object is to provide a device of this kind wherein flash tubes are formed integrally therewith.

A further object is to provide a series of radially spaced, integrally formed Bunsen tubes, with flash tubes integral therewith, and spaced therefrom.

30 A further object is to provide a Bunsen tube having a burner bowl removable therefrom, whereby a separate burner structure may be designed to suit any purpose, and whereby a port may be provided for injection of gas into the flash tube.

35 A further object is to provide a combination valve for this structure compact in design so as to fit therein, and including control for all the burners, and also having a pilot control integral therewith.

40 A further object is to design the Bunsen tubes so that the valve and projecting spuds may be fitted therein. This may be done by cutting out portions of the Bunsens for interfitting the valve.

45 A further object is to employ this cut-out portion as an air inlet to provide primary air for the Bunsen.

The assembly is applicable to any usage requiring several burners. In the appended description, it is described in connection with a top burner assembly for gas ranges, but this is only 50 by way of illustration.

With these and other objects in view, the invention is disclosed in the following specification, and drawings, wherein:

55 Fig. 1 is a plan view of the device partially cut away.

Fig. 2 is a horizontal sectional view of the valve used with the device.

Fig. 3 is a section on line 3—3 of Fig. 1.

Referring to the drawings, 10 indicates a unitary casting having four branches thereon, 11, 12, 13 and 14 radiating from a common center portion. On each of these extensions is secured burner 15. A valve 16 is located in the center portion and is adapted to control the flow of fuel to all of the burners.

10 As shown, each of the extensions comprises a Bunsen or mixing tube 18 and a flash tube 19 formed integrally with the Bunsen tube and the four units are integrally joined by a web portion 20 forming a part of the center portion of the 15 assembly.

Referring in particular to Fig. 3, each Bunsen extends radially from the center of the assembly. Fastened to each is a burner bowl element, generally indicated at 21, and having a screw connection 22 with the Bunsen tube. An opening 23 in the Bunsen registers with an opening 24 in the bowl whereby gas may flow from the Bunsen into the bowl. As shown, the bowl includes an outer overturned flange 25 and an inner cylindrical portion 26 having a shoulder thereon. Slidably mounted over the body is a flange member 27, the flange portion of which extends out over the overturned portion of burner flange 25, so as to provide a slot-like gas outlet 28. The second flange member 27 has an inner cylindrical portion 29 engaging with the cylindrical portion 26 of the bowl member and designed so as to provide a space having air outlets 30 therein. A web member 31 extends across cylindrical portion 26. Element 29 is capped, as shown, and secured thereto by a rivet or the like is an aeration plate 32. Plate 32, and second flange member 27, are fastened to bowl 21 by a screw 33, threaded into web member 31. By this means secondary air 35 from underneath the burner may pass upwardly through cylindrical portion 26 around web 31, and through ports 30 where it is directed by plate 32 outwardly to a point adjacent to the gas slot 28.

40 As heretofore described, flash tube 19 is formed integrally with Bunsen 14, and, as here shown, is formed as a single casting therewith. The tube is raised off the Bunsen by two webs 34. The burner bowl is provided with port 35 to direct gas into the flash tube. Raising the flash tube permits the port 35 to be completely surrounded by secondary air, whereby to support the flame thereat, after the burner has ignited.

45 The valve 16, heretofore referred to, has therein a passage 36 communicating with the inlet 37 50 55

55

thereof and controlled by a needle screw 38 having a lock nut 39 thereon. Port 36 at the top thereof has a machined screw fitting 40 fastened therein and adapted to direct the flow of gas leaving passage 36 to form a pilot device. The valve 16 has secured therein spud elements 41 to direct gas into each of the Bunsen tubes. Each Bunsen is cut away as at 42 to provide air inlets the size of which may be adjusted by a shutter plate 43. Each opening 42, it will be observed, extends outward as at 44 and around the end of the Bunsen, whereby with plate 43 moved out of position, the valve may be dropped out from under the burner assembly, passageways 42 and 44 permitting the spuds to be removed from the Bunsens. Each Bunsen is likewise provided with a rest 45 that may rest upon any suitable support in the range top.

Referring more particularly to Fig. 2, the valve 20 used herewith includes a body member 50 having inlet 37 that extends into the bottom thereof as shown in Fig. 3. Two tapered bores 51 and 52 are formed in body member 50. A T-shaped passageway 53 provides communication between inlet 37 and both taper 51 and taper 52. As will be understood, a similar T-shaped passage 54 likewise provides additional communication between inlet 37 and the two said tapered bores 51 and 52.

30 The valve provides four outlets, one to each of the Bunsen tubes. The outlets are designated 55, 56, 57 and 58. A passageway 59 is drilled into the housing 50 and extends almost therethrough. This passageway provides the T portion of inlet passage 53, and likewise provides outlets from the tapered bores on the opposite sides that lead to right angle passageways 60 and 61 communicating respectively with outlets 55 and 56. A plug 57 is located as shown, to close up the end of passage 40 59. In a like manner a passage 62 is extended almost all the way through the housing and provides communication from inlet passage 54 to the respective right angle passageways 63 and 64 leading respectively to outlets 58 and 57. Passage 45 62 is plugged as at 65. Each of the right angle passages 60, 61, and 63 and 64 may be drilled into the body and plugged as at 66.

Within the tapered bore 51, which is identical with the structure in tapered bore 52 so that only 50 one will be described, is fitted a dual plug control. The first of these two plugs is designated 70 and has extending from one end thereof a threaded projection 71 extending outside of the housing and surrounded by a spring and lock nut device 55 72 and will maintain the plug in close fit in the tapered bore. Extending from the opposite end of plug 70 is a stem 73 secured to the plug and forming a means for rotating the same. This plug is provided with a transverse passageway 74 60 adapted to provide communication between inlet passageway 53 and outlet passageway 55, 60 and 55.

A second plug 80 is fitted in bore 51 in tandem with plug 70. This plug is axially drilled to permit handle 73 to extend therethrough. A sleeve 81 terminating in a handle and surrounding stem 73, is secured to this plug for rotating it. A plate 82 is secured by a screw to the end of the housing and maintains a spring 83 acting against plug 80 70 to hold the plug in place. This plug is provided with a peripheral passageway 84 extending half way therearound, which passageway will establish communication between inlet 54 and outlet 62, 63, and 58.

75 The operation of the valve is as follows:

Inlet 31 is designed to be connected to a gas main leading preferably from the back of the stove. Gas then flows into passages 53 and 54 where it is led up to all of the four plugs. To admit gas to outlet 55 which will be connected to the Bunsen of branch 11, stem 73 is rotated to the position shown in Fig. 2 wherein passageway 74 will register with passage 53 and passage 59 whereby gas is conducted through said passages and passage 60 with outlet 55. To cut this burner off, it is simply necessary to rotate the plug until passage 74 therein no longer registers with passageway 53. The control of outlet 56 is identical, it being operated by its corresponding handle identically with outlet 55.

To operate the burner connected with branch 14, stem 81 is rotated until peripheral passageway 84 registers with passages 54 and 62 whereupon gas will flow from passages 54 through peripheral passage 84, passage 62, passage 63 and 20 outlet 58. To shut off this burner, stem 81 is rotated by its handle until the peripheral passage 84 no longer registers with passage 54. In like manner the burner on branch 13 is controlled by the rotation of its handle.

25 Thus each of the burners may be separately adjusted to suit its own particular needs without affecting the adjustment of any of the others. At the same time a unitary valve structure is provided requiring a minimum number of parts and 30 also requiring a minimum of space so as to fit within the available space in the assembly.

In assembly the entire structure the burner bowls are secured to their respective Bunsens. All shutters 43 are then opened and the valve is inserted therein from the bottom and, if desired, may be secured thereto by screws although normally it will be adequately supported on the gas inlet pipe. Inlet 37 of the valve is then joined with the fuel line. The pilot flame at 40 is then 40 ignited and adjusted by means of needle screw 38. It is locked in adjusted position by lock 39. Then each burner is turned on by its respective valve handle whereupon gas flows out of port 35 into the flash tube and back to the pilot. This 45 gas ignites at the pilot, flashes back through a tube and ignites gas issuing from the burner port 28. Each shutter 43 may then be adjusted to give the proper mixture in its Bunsen tube.

The handles of the valve may be led out into a 50 cluster or front panel on the stove where they form a neat attractive and convenient control device to allure the housewife to their use.

At any time that any adjustment is necessary it may be readily effected since the controls are 55 all in the center of the range.

Having described the assembly, what is claimed is:

1. A device of the character described comprising a one piece base member, a plurality of mixing tubes integrally formed therewith, said tubes radiating from a common center and the adjacent ends of said tubes and said base providing a definite space between such tube ends at said common center, a valve device removably mounted in said space, gas directing projections on said device extending into said mixing tubes, each of said tubes having a cut-away portion at one side to permit the unit assembly of said valve device with said base member, and burner means operatively connected to the outer ends of said tubes.

2. A device of the character described comprising a base member, a plurality of mixing tubes, said tubes and base member being integrally joined, the adjacent ends of said tubes being 75

- spaced from one another to provide a definite space between the same and said base, a valve device fitted into said space, gas nozzle projections on said valve device extending into said mixing tubes, means on said tubes accommodating said projections to permit the unit assembly of said valve device and said integrally formed base mixing tube member, and burner means operatively connected to the outer ends of said tubes.
- 10 3. A device of the character described comprising a base member, a plurality of mixing tubes formed integrally therewith and radiating from a common center on said base member, the inner adjacent ends of said mixing tubes being spaced to provide a definite recess between the same and said base member, a valve device closely fitted into
- 5 said recess, a plurality of projections on said valve device extending into said mixing tubes, fuel regulating spuds on said projections, each of said mixing tubes having a cut-away portion adjacent their inner ends to permit the unit assembly of 5 said valve device with attached spuds into said recess, and a shutter adjacent each of said cut-away portions of said tubes whereby to provide means for regulating the air mixture adjacent the spuds within said tubes and said shutters acting to confine said spuds within said tubes to prevent the disassembly of said unitary base and tube member and said valve device.
